UNITED STATES PATENT OFFICE.

EDWARD L. CAMPBELL, OF WINONA, MINNESOTA, ASSIGNOR TO THE J. R. WATKINS COMPANY, OF WINONA, MINNESOTA, A CORPORATION OF MINNESOTA.

DESIGN FOR A VEHICLE TIRE OR CASING.

58,178.

Specification for Design. Patented June 21, 1921.

Application filed November 9, 1920. Serial No. 422,964. Term of patent 14 years.

To all whom it may concern:

Be it known that I, EDWARD L. CAMPBELL, a citizen of the United States of America, residing at Winona, in the county of Winona, State of Minnesota, have invented a new, original, and ornamental Design for a Vehicle Tire or Casing, of which the following is a specification, reference being had to the accompanying drawings, forming part thereof.

In the drawings:—

Figure 1 is a plan view of a section of a vehicle tire or casing showing my new design.

Fig. 2 is a cross section thereof on the line 2—2, Fig. 1.

Fig. 3 is a cross section on the line 3—3, Fig. 1.

I claim:—

The ornamental design for a vehicle tire or casing, substantially as shown.

EDWARD L. CAMPBELL.
